UNITED STATES PATENT OFFICE.

CARL SCHLÜNS, OF BERLIN-STEGLITZ, GERMANY, ASSIGNOR TO MERCEDES-BÜRO MASCHINEN UND WAFFEN-WERKE, OF BENSHAUSEN, THURINGIA, POST MEHLIS, GERMANY.

TYPEWRITING MACHINE WITH POWER DRIVE.

Original application filed July 28, 1923, Serial No. 654,446. Divided and this application filed June 2, 1925. Serial No. 34,444.

To all whom it may concern:

Be it known that I, CARL SCHLÜNS, citizen of the German Republic, residing at Berlin-Steplitz, Germany, have invented certain new and useful Improvements in Typewriting Machines with Power Drives, of which the following is a specification.

The present invention relates particularly to automatic return mechanism for power driven typewriters and is a division of my co-pending application Ser. No. 654,446 filed July 28, 1923.

According to the invention, the feeding of the paper carriage and the line-feed are carried out automatically from the source of mechanical power by the arrangement of a rope or band attached to the line-feed lever and wound around a drum through the action of the source of power. In order to start without shocks the movement of the paper carriage and the other feeding movements at the throwing in and out of gear of the power-coupling an elastic element, for instance a buffer spring, is inserted between the driving member and the driven member, said spring absorbing the shock produced at the throwing in gear of the coupling. The source of power may be temporarily coupled with the members to be driven by a toothed- or electro-magnetic coupling. The throwing in and out of this coupling is controlled automatically from the right hand or left hand margin-adjuster, or by the depression of a key. Care has further been taken that the usual possibilities of manipulation by hand of the movement of the paper carriage and of the line-feed are preserved.

The invention will be best understood from a consideration of the following detailed description taken in connection with the accompanying drawings forming a part of this specification, with the understanding that while on the drawings one embodiment of the invention is disclosed, the invention is not confined to any strict conformity with the showing of the drawings, but may be embodied in any manner which does not make a material departure from the salient features of the invention.

50 In the drawings:—

Fig. 1 shows in perspective front elevation a typewriting machine in which the ma-

chine proper is shown in elevation and the power coupling in section.

Fig. 2 is a plan view of Fig. 1.

Figs. 3 and 4 show details of the coupling mechanism shown in Fig. 1.

The movement of the carriage is controlled by the coupling shown in Figs. 3 and 4 on an enlarged scale.

In the worm case 71 fixed on the machine a bolt 72 is fixed on which the worm wheel 73 is rotatably mounted being secured against axial displacement by collar 74, screw 75 and washer 76. On the worm wheel a carrier disk 79 having a groove 78 is fixed by two screws 77.

In the machine frame itself a bush 81 with collar 80 is located which is threaded at the left end and adapted to be securely connected with the frame by means of a nut 82. A band pulley 83 is rotatably mounted on the bush 81 and has at its right hand side two single teeth 84. The band pulley is hollow and accommodates a spiral spring 85 attached on the one hand to bush 81 and on the other hand to the inner circumference of the band pulley 83, so that the spring 85 wound up, viewed in the direction of the arrow 86, acts upon the band pulley 83 in an anti-clockwise direction. The band pulley 83 is closed by a lid 87 fixed thereto and the whole is secured against axial displacement by the collar 80 of bush 81, adjusting ring 88 and adjusting screw 89.

In the bush 81 the shaft 90 is revolvably mounted and on this shaft a disk 91 is keyed and retained by a screw 92. A bolt 93 is laterally riveted on the disk and a roller 94 mounted on said bolt engages with a groove 95 of the disk 96 keyed on the cam shaft 11. The shaft 11, as described in my original application, serves as actuator for the type levers. At the opposite end of shaft 90 a carrier disk 99 having an aperture 98 is fixed by a bolt 97 so that the shaft 90 is secured against axial displacement. On the carrier disk 99 a roller 101 is rotatably fixed by a bolt 100, said roller engaging with the above mentioned groove 78 of the carrier disk 79 fixed on the worm wheel. In the annular groove 98 (Fig. 4) a block 103 is fixed by means of a screw 102, said block serving as abutment for the one end

of a spring 104, the other end of which bears against a block 106 fixed to a ring 105. This block 106 is inserted into the carrier disk 99 before the ring 105 is pushed over said disk. The ring 105 is fixed to block 106 by a screw 107 whereby the ring, which is rotatably mounted on disk 99, is secured against axial displacement. On the ring 105 a coupling disk 110 having teeth 108 and a groove 109 is fixed by means of keys 111 so that it is able to rotate together with the ring 105 on which it may however be displaced in axial direction.

The operation of the coupling is as follows:—

At the carriage 112 running down (Fig. 1) the pawl 113 of the right hand margin adjuster 114 runs up the shoe 115 of the upper key-locking-bar 116 which is movably mounted by means of a slot 117 at the right hand end on a screw 118 fixed to the frame and which is guided at the left hand end by means of slot 119 on a stud 120 of the set-off rod 121 which is constantly urged upwardly under the action of a spring not shown in the drawing. The upper key-locking-bar 116 is thus pressed first downward and at the further running down of the carriage it is pushed to the left under the abutment 123 on the stationary frame of the machine owing to the action exerted by the pawl 113 of the margin adjuster 114 upon the abutment 122. At this proceeding the locking known per se of all the keys is effected by the rod 121, and lasts during the return of the carriage and during the line-feeding.

Owing to the fact that the upper key-locking-bar is pushed to the left a lever 125 pivotally connected thereto by pin 124 is also drawn to the left, said lever 125 being hingedly connected at 126 with a lever 127 which is thus also pushed to the left. This lever 127 is keyed to a rotatable axle 128 on which further a lever 129 is keyed which consequently also executes an oscillation to the left and by the engagement known per se of this lever with the groove 109 of the coupling sleeve 110 driven from the motor M (Fig. 2) and rotated permanently through the intermediary of the worm wheel gear (Figs. 1, 3 and 4) this coupling sleeve is pushed to the left. The teeth 108 come thus in gear with the teeth 84 and the band pulley 83 is drawn along in the same direction of rotation as the coupling sleeve 110 (Fig. 3) which, seen in the direction of the arrow 86, rotates in anti-clockwise direction. A band 130, attached to the band pulley 83 is wound up and, guided over guide pulleys 131, 132, draws along a bar 133 movably mounted in the well known manner in the carriage (Fig. 2). This bar 133 is pivoted at 134 to the feed-lever 135 for the line-feeding and it effects the line-feeding in the well known manner. After the termination of

the line-feeding or at the extreme right hand position of the line-feed lever the carriage is drawn along and returned to its initial position. Towards the end of the return movement of the carriage the pawl 136 (Fig. 1) of the left hand margin adjuster 137 strikes against the abutment 122 of the upper key-locking-bar and pushes the same to the right, so that this bar, by means of the spring mentioned above acting upon rod 121, is brought back into its former position in front of the abutment 123 and the coupling is disengaged by means of the lever system 125, 127, 129. The kinetic energy communicated to the carriage by the upward movement is neutralized by the work done at the disengaging of the coupling so that the carriage arrives at the extreme right hand position without any shock. By depression of a key 138 mounted on rod 121 the upper key-locking-bar may be operated, in conjunction with tension spring 138', whereby the coupling is also thrown in so that the same operation begins anew. This releasing may be effected at any position of the paper carriage.

At the instant at which the coupling sleeve 110 comes in engagement with the band pulley a shock and a vibration would be produced in the machine if there were no special measures taken. This is avoided by the above mentioned arrangement of the spring 104 (Fig. 4) in the carrier disk 99 so that the running up of the carriage is started without shock.

The spring 85 in the band pulley 83 serves merely for stretching the band 130 when the carriage is running down or is being pulled up by hand.

Claims—

1. In a motor driven typewriter, a constantly rotating shaft, type keys, a type key locking element, a paper carriage, means for returning said carriage, a clutch for coupling said carriage-returning means to said constantly rotating shaft, a horizontally and vertically movable bar, connections between said bar and said key-locking element for actuating said key-locking element upon vertical movement of said bar, connections between said bar and said clutch for actuating said clutch upon horizontal movement of said bar, and cooperating lugs on said carriage and said bar for moving said bar vertically and horizontally.

2. In a motor driven typewriter, a constantly rotating shaft, type keys, a type key locking element, a paper carriage, means for returning said carriage, a clutch for coupling said carriage-returning means to said constantly rotating shaft, a horizontally and vertically movable bar, connections between said bar and said key-locking element for actuating said key-locking element upon vertical movement of said bar, connections be-

- tween said bar and said clutch for actuating said clutch upon horizontal movement of said bar, a cam and an abutment on said bar, a lug on said carriage for engaging at 5 one limit of movement of the carriage, first said cam for moving the bar vertically to lock the keys, and then the abutment for moving the bar horizontally to engage the clutch, a keeper under which the end of said 10 bar is moved upon said horizontal movement, a second lug upon said carriage for engaging said abutment, when the carriage reaches its other limit of motion, for moving said bar horizontally to throw the clutch 15 out and release said bar from said keeper, and spring means for returning said bar to initial vertical position.
3. In a motor driven typewriter, a paper carriage, and return means for said carriage, comprising a constantly rotating shaft, a rotatable winding drum concentrically mounted relatively thereto, said drum having a lateral lug thereon, a cylindrical coupling member adjacent said drum 20 and rotating with said shaft, a circumferentially grooved annulus splined on said 25
- coupling member, said annulus having a lateral lug thereon, a fork engaging said circumferential groove whereby said annulus is adapted to be displaced toward said drum 30 for engaging said lugs, and a cable connected to said carriage and adapted to be wound on said drum.
4. In a carriage return device for motor driven typewriters, a constantly rotating shaft, a free clutch element concentrically mounted relative thereto, and a constantly rotating clutch element on said shaft comprising three concentric annular members, the innermost of said members being fixed 35 to said shaft, yieldable means interposed between said innermost member and the intermediate member for allowing relative rotational movements of the two, the outmost of said members being splined to said intermediate member, and means for displacing said outmost member for engaging said free clutch element. 40

The foregoing specification signed at Berlin this 18th day of March, 1925.

CARL SCHLÜNS.
